UNITED STATES PATENT OFFICE.

OTIS L. BEARDSLEY, OF AUSTIN, ILLINOIS.

CHAIR.

SPECIFICATION forming part of Letters Patent No. 694,457, dated March 4, 1902.

Application filed July 10, 1899. Serial No. 723,255. (No model.)

To all whom it may concern:

Be it known that I, OTIS L. BEARDSLEY, a citizen of the United States, residing at Austin, in the county of Cook and State of Illinois, have invented a certain new and useful Improvement in Chairs, (Case No. 2,) of which the following is a full, clear, concise, and exact description.

My invention relates to a chair, and more particularly to a chair of the kind known to the trade as iron chairs, of which the framework—that is, the legs, rounds, and back—are made of iron or steel rods or heavy wire, usually twisted together.

My object is to produce a strong chair of graceful design which will be cheap to manufacture and which will permit the legs to be readily detached and folded together into small compass for shipment.

In accordance with my invention the legs of the chair, which are preferably made of U-shaped pieces or loops of wire twisted together, are detachably secured to the seat portion and a separate brace is provided, forming the rounds, to which the legs are fastened in such a manner that when detached from the seat they may be folded together about the brace as upon a hinge until they are all approximately in one plane. It will be appreciated that this flattened form will take up very little room in shipment as compared with the space that would otherwise be occupied. It will also be seen that the legs are continuously double-stranded from top to bottom and are reinforced by the brace.

My invention will be more particularly described by reference to the accompanying drawings, wherein—

Figure 1 is a perspective view of a chair constructed in accordance with my invention, and Fig. 2 is a plan view showing the legs and brace detached from the rest of the chair and folded together in a convenient flat form for shipment.

Each of the four legs of the chair is formed of a single loop of iron rod or heavy wire twisted together, the free ends being formed into eyes $a' a'$. Each leg may then be secured to the seat B of the chair by bolts $c c$ passing through these eyes $a' a'$. Each leg is so twisted as to be symmetrical, and the ends of the loop of wire which forms the leg are adapted to be

fastened to the seat adjacent to one another, as shown. About midway between the top and bottom of the legs is provided the square brace d , which is preferably made of a single piece of wire bent in the form of a square, with projecting loops at its four corners which are linked into the four twisted legs $a a$, respectively, the ends of the wire forming the brace being preferably brazed or welded together to form a continuous or endless piece. The engagement between the loops at the corners of the square brace and the legs of the chair is firm, so that the brace will be effective and will not permit the chair to wobble. The particular advantage of this construction will, however, be seen most readily by reference to Fig. 2, which shows the legs of the chair detached from the seat and folded together. This folding is accomplished by simply turning each leg upon the looped end of the brace as upon a hinge, so that the upper ends of the legs occupy the center of the chair and the outer ends thereof radiate from the corners thereof, forming a star-shaped figure. It will be apparent that the parts illustrated in Fig. 2 may thus be packed in much less space than would be required if they were rigidly held in their normal positions. The legs also are thus made continuously double-stranded from top to bottom and are additionally strengthened by the loops of the brace.

It will be apparent that my invention is capable of modification, and chairs constructed in accordance therewith may be given widely-different forms, which will readily suggest themselves to those skilled in the art. I do not therefore desire to be understood as limiting myself to the precise construction shown; but,

Having thus described my invention, I claim as new, and desire to secure by Letters Patent, the following:

1. As a new article of manufacture, a chair comprising a seat b , detachable legs $a a$ formed of twisted loops of wire, the ends of the wire forming each leg or loop being adapted to be attached to the seat adjacent to one another, and a brace d having loops in which the twisted legs are linked, whereby the said legs, when detached from the seat, may be folded together about said brace into a star-shaped plane figure, substantially as described.

2. As a new article of manufacture, a chair comprising a seat *b*, detachable legs *aa* formed of loops of heavy wire twisted together, the ends of the wire forming each leg or loop being symmetrical and adapted to be attached to the seat adjacent to one another, and a brace *d* of wire in the shape of a polygon, said brace having loops at its corners in which the twisted legs are linked, whereby the legs,

when detached from the seat, may be folded together about said loop into a plane, substantially as set forth.

In witness whereof I hereunto subscribe my name this 6th day of July, A. D. 1899.

OTIS L. BEARDSLEY.
